Gusson & Houson

UNITED STATES PATENT OFFICE.

DAVID G. McCAA, OF LANCASTER, PENNSYLVANIA.

MICROPHONE.

Application filed June 4, 1918. Serial No. 238,177.

To all whom it may concern:

Be it known that I, DAVID G. McCAA, a citizen of the United States, residing in Lancaster, Pennsylvania, have invented ⁵ microphones, of which the following is a specification.

One object of this invention is to provide a microphone particularly adapted for use in wireless telephone systems by reason of its ¹⁰ being capable of dissipating the relatively large amounts of electrical energy characteristic of the more successful forms of this class of apparatus, the construction including a novel arrangement of heat radiating vanes ¹⁵ designed to be cooled either by air or liquid.

A further object of the invention is to provide a microphone whose construction shall be such as to fit it for carrying relatively heavy currents of electricity, i. e., instead of ²⁰ being limited to use in circuits carrying in the neighborhood of one-quarter of an ampere, the microphone constructed according to my invention shall be capable of carrying from three to five amperes.

²⁵ I also desire to provide a microphone particularly adapted to employ a heat conducting electrical insulator so disposed as to facilitate the radiation of the heat generated in the instrument under conditions of use.

³⁰ Another object of my invention is to provide a device of the class noted which shall be particularly adapted for use in a position in which the carbon granules rest upon and are supported directly by the diaphragm, ³⁵ the construction being such that the instrument is not only efficient but is sensitive in that for given movements of the diaphragm it gives increased resistance changes in the circuit in which it is included.

⁴⁰ It is also desired that the microphone constituting my invention shall have its parts so arranged that the heat produced under conditions of use shall be generated not between the diaphragm and the granules but ⁴⁵ between the latter and an interior terminal in the form of a carbon button.

These objects and other advantageous ends I secure as hereinafter set forth, reference being had to the accompanying drawings, ⁵⁰ in which—

Fig. 1 is a central vertical section illustrating the detail construction of a microphone constructed according to my invention.

⁵⁵ Fig. 2 is a horizontal section on the line 2—2, Fig. 1;

Figs. 3 and 4 are perspective views of the

conducting plate and damping spring forming part of the instrument shown in Figs. 1 and 2;

Fig. 5 is a central vertical section of a modified form of microphone;

Fig. 6 is a horizontal section on the line 6—6, Fig. 5; and

Fig. 7 is a perspective view of the form of damping spring preferably used in that ⁶⁵ form of instrument shown in Fig. 5.

In Figs. 1 to 4 of the above drawings, 1 represents a cup-shaped, substantially cylindrical casing preferably of brass or copper, closed at one end and having threaded ⁷⁰ to it an inwardly flanged ring 2 designed to clamp over its otherwise open end a carbon diaphragm 3.

The flange of this ring also clamps against the outer portions of said diaphragm at two ⁷⁵ opposite portions thereof, a plate 4 of copper foil (Fig. 3) preferably made with a central circular portion normally pressed against the central part of the diaphragm 3 by the damping spring 5.

⁸⁰ This latter consists of a spring metal strip having mounted on one end a cushion 6 of asbestos or other poor heat-conductor and has its opposite end clamped against the outer edge of the ring 2 by a cover plate 7 ⁸⁵ held to said ring by screws 8. This plate has an outwardly flanged opening formed through its central part for the reception of a horn or mouth piece 9 whose open outer end extends in a line at right angles to that of ⁹⁰ the center line of the casing 1 and of the cover plate 7.

⁹⁵ Mounted centrally within the casing 1 is a substantially cylindrical metal shell 10 extending from the top or upper end thereof to within a short distance of the diaphragm and a series of radially disposed vanes 21 extend between this shell and the curved portion of the casing 1 in such numbers as to rapidly conduct heat to the latter ¹⁰⁰ from said shell, it being obviously immaterial whether or not the vanes, shell and casing are integral or are structurally independent but in intimate contact.

Mounted within the shell 10 is an inverted ¹⁰⁵ cup-shaped container 11 which according to my invention is characterized by being not only a poor electrical conductor but a good conductor of heat and as typical of a material answering this requirement, I preferably ¹¹⁰ employ soapstone or talc.

Said container 11 is centrally recessed to

provide a chamber into which extends a conductor 12 in the form of a threaded rod which within the recess 13 has mounted upon it terminal member formed by a carbon button 14 between which and the top of said cavity are confined one or more metal washers 15. The conductor 12 is insulated from the casing 1 and has mounted on its outer end a metal washer 16 and a retaining nut 17 whereby it with the button 14 are rigidly held in place.

Within the cavity 13 surrounding and engaging the carbon terminal member 14, is a mass of carbon granules 18 which when the casing 1 is in its normal operative position shown, rest upon and are supported by the diaphragm 3, it being noted that while the insulating cup 11 is spaced away from said diaphragm so as not to interfere with its free vibration, the distance between these members is not sufficient to permit escape of the granules 18.

In order to prevent air packing, I provide a set of openings 19 into the cells or compartments formed by the vanes 21, shell 10 and casing 1 and other openings 20 in the flat top of said casing so that there is a free flow of cooling fluid such as air into and out of said chambers or cavities.

Under conditions of use the instrument is supported by any suitable means in the position shown in Fig. 1, that is, with its carbon granules 18 resting upon and supported by the diaphragm 3 as well as engaging the carbon button 14. As a result of this construction and position, the diaphragm is vibrated and when current flows through the central conductor 12, the carbon button 14, the granules 18, the diaphragm 3 and a second terminal (not shown) electrically connected to the casing 1, there is practically no heat generated between said granules and the diaphragm.

On the other hand by far the greater quantity of the energy dissipated occurs in the form of heat produced between the carbon granules and the carbon button or terminal member 14 and because of the heat conducting characteristic of the granule container or cup 11, this heat is rapidly transferred to the shell 10 and thence through the vanes 21 to the outer or main casing 1, being quickly dissipated by the air both inside and outside of this latter. As a result, relatively large currents may be safely and continuously employed in the instrument.

The asbestos or other non-conducting cushion 6 on the damping spring 5 effectively prevents this latter being affected by any heating of the diaphragm which may occur and such heating is in any event materially reduced by the use of the body 4 of metal foil which rapidly conducts the heat from the center of said diaphragm to

the parts 1 and 2 of the casing, from which the dissipation of heat is aided by the circulation of air through the openings 19 and 20.

In that form of my invention shown in Fig. 5 I have substituted a metal ring 22 for the main part of the casing 1 and as before hold the diaphragm 3 and the body of metal foil 4 to the lower end or edge of this ring by a clamping ring 2, likewise damping the vibration of the diaphragm and maintaining the foil body 4 in intimate engagement with the center of the latter by a cushion 6^a on the end of a damping spring 5^a which as before is clamped to the ring 2 by a cover plate 7.

The main casing in this case takes the form of a substantially cylindrical shell 23 having an upward tubular extension 24 in which, as before, I mount an electrical insulating heat conducting cup or container 25 having a portion projecting into the extension 24. As before, a conductor in the form of a rod 26 threaded at its ends extends through the extension into the cup 25 in which it has mounted on it a carbon button or terminal member 14^a engaging a metal washer 15^a which it holds against the top of the cavity in said cup. The conductor 26 with its attached parts, is held in place by a nut 17 threaded on its outer end and engaging a metal washer 16.

In this instance the casing 23—24 is integral with the ring 22, to which it is connected by a radially extending portion 28. The carbon granules 18 are as before supported by the diaphragm 3 within the cavity 13 of the insulating structure 25 and extend around and in contact with the carbon button 14^a. In order to rapidly dissipate the heat generated under operating conditions between said button and said granules, I attach to or form integral with the shell 23 and its extension 24 a series of radiating vanes 21^a whose sides are in free contact with the air.

As before, there is a horn or mouth piece 9 extending at right angles from the central opening 30 of the cover plate 7 and therefore at right angles to the center line of the instrument, which as in the case shown in Fig. 1, is designed for use in the position shown in Fig. 5 with the carbon granules carried upon and in intimate contact with the diaphragm 3. This form of the invention, like that of Figs. 1 and 2, is also capable of operation with relatively heavy currents and is adapted to dissipate without injury the relatively large amounts of heat generated.

I claim:

1. The combination in a microphone of an inverted cup-shaped container formed of a heat conducting insulator; a metallic shell surrounding the container; a diaphragm

- normally closing the otherwise open end of said container; a terminal member extending into the container; a body of granular electrical conducting material resting on and supported in the container by, the diaphragm; and heat radiating elements formed integral with the shell of said container for dissipating heat generated between granular material and the terminal member. 5
2. The combination in a microphone of a soap stone container; a terminal member extending into the same; a diaphragm forming a closure for said container; and a body of granular electrical conducting material retained in the container by the diaphragm and electrically connecting the latter with the terminal member. 10
3. The combination in a microphone of a soap stone container; a terminal member extending into the same; a diaphragm forming a closure for said container; a body of granular conducting material retained in the container by the diaphragm and electrically connecting the latter with the terminal member; a metal shell surrounding the container; and heat radiating vanes conductively associated with said shell. 15
4. The combination in a microphone of a metal casing; a metal shell mounted within the same; heat radiating vanes connecting said casing and shell; a body of heat conducting electrically insulating material within the shell and formed with a bottom-opening cavity; a diaphragm closing said cavity; a terminal member extending into the cavity; and a mass of granular conducting material retained by the diaphragm in said cavity in position to electrically connect it with the terminal member. 20
5. The combination in a microphone of a casing; a container made of good heat conducting electrically insulating material and mounted within the casing; a diaphragm normally closing the container; a terminal member extending into the container; and a mass of granular electrical conducting material connecting said terminal member with the diaphragm, there being openings into the space between the container and the casing for the admission and exit of cooling fluid. 25
6. The combination in a microphone of a cellular metal casing having openings into its compartments; a container of heat conducting, electrical insulating material within the casing; a terminal member within the container; a diaphragm forming a closure for the container, and a body of granular electrically conducting material connecting the diaphragm with the terminal member. 30
7. The combination in a microphone of a diaphragm; a terminal member; a body of granular electrical conducting material confined between the diaphragm and said member in position to be supported by said diaphragm; with a damping member in the form of a spring rigidly held at one end and having a heat insulating cushion on its opposite end positioned to exert pressure upon the diaphragm. 35
8. The combination in a microphone of a carbon diaphragm; a container normally closed by said diaphragm; a terminal member in the container; a body of granular electrical conducting material in the container electrically connecting the diaphragm and the conducting member; a body of metal foil extending across the diaphragm; with a damping spring including a heat insulating cushion engaging the metal foil in position to act through the same upon the central part of the diaphragm. 40
9. The combination in a microphone of a soap stone container having a bottom opening; an electrical conductor extending into the container; a carbon button on said conductor within the casing; a carbon diaphragm normally closing the opening of the container; with a body of granular carbon supported by the diaphragm and in electrical engagement with the carbon button. 45
10. The combination in a microphone of a soap stone container having a bottom opening; an electrical conductor extending into the container; a carbon button on said conductor within the casing; a carbon diaphragm normally closing the opening of the container; a body of granular carbon supported by the diaphragm and in electrical engagement with the carbon button; and means for radiating the heat generated between the granular carbon and the carbon button, consisting of heat radiating metal vanes in intimate mechanical connection with the external surface of the soap stone container. 50

In witness whereof I affix my signature.
DAVID G. McCABA.
